UNITED STATES PATENT OFFICE.

THOMAS EMBRY, OF PANQUI, PHILIPPINE ISLANDS.

SAFETY-ENVELOP.

No. 918,982.

Specification of Letters Patent.

Patented April 20, 1909.

Application filed September 15, 1908. Serial No. 453,191.

To all whom it may concern:

Be it known that I, THOMAS EMBRY, a citizen of the United States of America, residing at Paniqui, in the Province of Tarlac, 5 Philippine Islands, have invented new and useful Improvements in Safety-Envelops, of which the following is a specification.

This invention relates to safety envelops, and one of the principal objects of the same 10 is to provide simple and efficient means for sealing the envelop so that it cannot be opened without detection.

Another object of the invention is to provide an envelop having a metal clasp for 15 holding the folding flap in connection with the envelop in a manner to prevent the opening of an envelop without mutilating the same, and thus indicating that the envelop has been tampered with by an un- 20 authorized person.

These and other objects may be attained by means of the construction illustrated in the accompanying drawing, in which,—

Figure 1 is a rear face view of the envelop 25 sealed. Fig. 2 is a plan view of the blank for forming the envelop. Fig. 3 is a plan view and partial section of the clasp for securing the folding flap in place and sealing the envelop. Fig. 4 is a plan view of the 30 blank for forming the female member of the clasp. Fig. 5 is a sectional view taken on the line 5—5 of Fig. 3.

Referring to the drawing, the numeral 1 designates the front side of the envelop; 2 35 is the rear flap; 3, 3, the side flaps, and 4, the folding flap. In folding the envelop the side flaps 3 are first folded, and the inner ends of said flaps extend one beyond the other. The flap 2 is then folded, and the envelop 40 is ready for securing the clasp thereto.

The female member of the clasp consists of a shank 5 having securing prongs 6 extending therefrom, and a tubular portion 7 is formed on the opposite end of said member 45 by folding the enlarged portion 8 of the blank shown in Fig. 4. A spring 9 preferably formed of wire is bent upon itself and secured in the tubular portion of the female member by means of a stud 10. The inner 50 edges 11 of the tubular portion of the clasp are bent inward between the two members of the spring, as shown in Fig. 5, to hold the spring in place. An ear 12 cut from each

side of the hollow or tubular member is bent inward to bear against the side arm 55 of the spring 9. The terminal ends of the spring 9 are bent inwardly, as at 13.

The male member of the clasp consists of a plate 14 having securing prongs 15 projecting therefrom, and an arrow headed engaging member 16 designed to be engaged by the inwardly bent ends 13 of the spring 9, as shown in Fig. 3, and to prevent the withdrawal of said arrow headed member without mutilation of the envelop. 65

The female member is secured to the back 2 and to the overlapped ends of the side flap 3 by bending down the prongs 6 and passing them through the back 2 and said overlapping portions of the side flaps 3. The male 70 member 14 is secured to the folding flap 4 by passing the body of the member through slits formed in the flap and by means of the prongs 15 engaging said flap. The body portion 5 of the female member is secured 75 behind a strap *a* in the back portion 2 of the envelop, and the prongs 6 are bent inwardly after having been passed through the material.

When the two clasp members are engaged 80 the envelop is effectually sealed and cannot be opened surreptitiously. The envelop can be manufactured at slight cost; there are no projecting portions, and when once sealed cannot be opened except by the person to 85 which the envelop is addressed without detection.

I claim:—

A safety envelop having a two-part clasp secured thereto, one member of said clasp 90 comprising a tubular portion, a spring secured within said tubular portion by a stud and by the inturned edges of said tubular portion, lugs bent inwardly against said spring, and an arrow-headed engaging member 95 secured to the sealing flap of the envelop and adapted to engage said spring and to prevent withdrawal therefrom without mutilation.

In testimony whereof I affix my signature 100 in presence of two witnesses.

THOMAS EMBRY.
